WALLACE M. GRAY, OF CINCINNATI, OHIO

TRACK-LUBRICATING APPARATUS

Application filed August 1, 1928. Serial No. 296,768.

My invention relates to railway track lubricating apparatus. One of its objects is to provide improved and reliable apparatus adapted to deliver the lubricant to the throat of the car wheel flanges without perforating the rails or reducing the cross-section of the rails. Another object is to provide improved and reliable and relatively inexpensive means attached to the side of the rail to engage and deflect the car wheel flanges away from the side of the rail to permit the lubricant discharge tube to extend up along the side of the rail and discharge lubricant directly to the throat of the car wheel flanges, and to protect such lubricant discharge tube from injury due to the passage of the car wheels and their flanges. My invention also comprises certain details of form and arrangement and combination of components, all of which will be fully set forth in the description of the accompanying drawings, in which:

Fig. 1 is a plan of a section of railway track illustrating my improved apparatus applied thereto.

Fig. 2 is a plan of a section of rail illustrating a modification of Fig. 1.

Fig. 3 is a view similar to Fig. 2 illustrating another modification.

Fig. 4 is an enlarged sectional detail taken on line 4—4 of Fig. 1.

Fig. 5 is an enlarged sectional detail taken on line 5—5 of Fig. 2.

Fig. 6 is an enlarged sectional detail taken on line 6—6 of Fig. 3.

The accompanying drawings illustrate embodiments of my invention. In Figs. 1 and 4, the rails 15 and 16 adjacent to a switch or other curve in the track 17 are designed to be provided with apparatus adapted to apply a lubricant to the flange or flanges 18 of one or more pairs of car wheels 19 mounted upon axles 20, as they pass along the track and thereby to enable the lubricated car wheel flanges to apply lubricant to the side of the track upon the inside of the curve where the car wheel flange is crowded by inertia against the side of the outer rail of the track in rounding a curve.

It is desirable that the lubricant be applied to the throat of the car wheel flanges. In

order to reliably apply the lubricant to the throat of the flange, or junction of the flange with the tread of the car wheels and at the same time simplify the structure and avoid drilling, perforating or reducing the rail 55 cross-section and thereby weakening the rails, I provide a forged bar 22 which is tapered at its opposite ends and which is attached to one of the rails adjacent to a switch or a curve, for instance by electrically welding said bar 60 22 to the inside of the rail at 23 along the exterior of the joint between said bar 22 and the rail. A rib 24 along the middle portion of the bar 22 is bent outwardly from the rail at the lower edge of the bar 22 below the path 65 of the car wheel flanges thereby facilitating reaching the under edge of the bar 22 where it abuts the rail to weld the lower edge of the bar 22 as well as the upper edge of the bar 22 to the rail. A sheet metal stamping 70 or trough 25 is electro-welded to the rib 24 to form a header to receive lubricant from a pipe connection 26 and to distribute lubricant through a series of substantially vertical perforations 27 through the bar 22 into position to contact with the throat of the car wheel flanges.

The lubricant may be supplied intermittently through the pipe 26 under pressure by any desired type of lubricant feeding mechanism. As illustrated in Fig. 1 a lubricant storage reservoir 28 is located beneath the track 16 and a lubricant pump is located within said storage reservoir with the upper end of the pump plunger 29 located in position with reference to the rail 16 so that the flanges of the car wheel traveling upon rail 16 will serve to successively depress the pump plunger 29, which is returned by a spring to thereby intermittently pump lubricant from 80 the reservoir 28 through a pipe 30 to the pipe 26 through a flexible hose connection 31, which enables the pipe section 29 to move relative to the pipe section 26 without danger of strain or fracture of the apparatus. The 85 member 22 is engaged by the car wheel flanges which are thereby deflected away from the edge of the rail a distance equal to the thickness of the member 22, and the lubricant discharge tubes or ports are thus protected from 90 95 100

injury and enable the lubricant to be discharged in position to contact with the throat of the car wheel flanges.

In the modification Figs. 2 and 5, tapered metal members 32 and 33 are built out by electro-welding for instance from the inside edge of the rail 34, corresponding to the rail 15 of Fig. 1, with an open eye or vertical recess 35, designed to receive and to protect from injury a short tube section 36, which is threaded into a block 37 attached by bolts 38 and nuts 39 to the rail 34. A pipe section 40 corresponding to the pipe section 26 of Fig. 1 provides an intermittent supply of lubricant under pressure which is discharged from the upper end of the tube 36 in position to contact with the throat of the car wheel flanges, without perforating or weakening the rail 34.

In the modification Figs. 3 and 6, a tapered bar 41 corresponding to the bar 22 of Fig. 1, is either attached to or built up by electro-welding for instance against the inner side of the rail 42, corresponding to the rail 15 of Fig. 1. The bar 41 is provided with an eye 43, into which projects a lubricant discharge tube 44 threaded into a block 45 attached by bolts 46 and nuts 47 to the rail 42. Lubricant under pressure is supplied intermittently through the pipe 48, corresponding to the pipe section 26 of Fig. 1, and discharged from the upper end of the tube 44 in position to contact with the throat of the car wheel flanges. The eye 43 serves to protect the tube 44 from injury and the bar 41 deflects the car wheel flange away from the face of the rail for that purpose.

The apparatus herein shown and described is capable of considerable modification within the scope of the claims without departing from the spirit of my invention.

What I claim is:

1. Track lubricating apparatus comprising in combination with the rails of a track and means to intermittently supply lubricant for lubricating one of the rails, a member rigidly attached to the inner edge of one of the track rails and projecting inwardly therefrom in position to be engaged by the flanges of passing car wheels and to deflect them inwardly, said projecting member being provided with a channel protected from the action of the car wheel flanges and through which lubricant is adapted to be fed upwardly into position to contact with the throat of the car wheel flanges as they pass over said projecting member.

2. Track lubricating apparatus comprising in combination with the rails of a track and means to supply lubricant for lubricating one of the rails, a member rigidly attached to the inner edge of one of the track rails and projecting inwardly therefrom in position to engage the flanges of passing car wheels and space the car wheel flanges so engaged away

from the edge of the rail, and a lubricant discharge conduit passing upwardly through said projecting member and adapted to feed lubricant into position to contact with the throat of the car wheel flanges as they pass 70 said projecting member.

3. Track lubricating apparatus comprising in combination with the rails of a track and means to supply lubricant for lubricating one of the rails, a member tapered at one end and rigidly attached to the inner edge of one of the track rails and projecting inwardly therefrom in position to engage the flanges of passing car wheels and space the car wheel flanges so engaged away from the edge of the rail, and a lubricant discharge conduit passing upwardly through said projecting member and adapted to feed lubricant into position to contact with the throat of the car wheel flanges as they pass 80 said projecting member.

4. Track lubricating apparatus comprising in combination with the rails of a track and means to supply lubricant for lubricating one of the rails, a member rigidly attached to the rail and projecting inwardly from the inner edge of one of said rails in position to engage the flanges of passing car wheels and space the car wheel flanges so engaged away from the edge of the rail, and a lubricant discharge port in the upper face of said projecting member adapted to discharge lubricant in position to contact with the throat of the car wheel flanges as they pass 90 said projecting member.

5. Track lubricating apparatus comprising in combination with the rails of a track and means to supply lubricant for lubricating one of said rails, a member tapered from an intermediate portion toward each end thereof and rigidly attached to one of the rails in position to project inwardly from the inner edge of the rail to which it is attached in position to engage the flanges of passing car wheels and space the car wheel flanges so engaged away from the edge of the rail, and a lubricant discharge port at the upper face of said projecting member in position to discharge lubricant in position to contact with the throat of the car wheel flanges as they 105 pass 110 said projecting member.

In testimony whereof I have affixed my signature.

WALLACE M. GRAY.
